UNITED STATES PATENT OFFICE.

THOMAS M. BRINTNALL, OF LOS ANGELES, CALIFORNIA.

REINFORCEMENT FOR MATCH BOXES.

Application filed October 11, 1924. Serial No. 743,029.

This invention relates to boxes of the sliding drawer type, such as are generally employed for carrying matches, and pertains more particularly to improvements in common pocket match boxes.

The principal object of my invention is to provide improvements in such match boxes whereby a box of matches may be carried in the pocket with greater safety.

Another object of the invention is to provide for strengthening common paper or veneer match boxes so that one may be carried in a pocket without danger of its being easily crushed or collapsed.

Another important object of the invention is to provide means for controlling movement of the sliding match containing members so that there is little or no tendency on the part of the user to fumble the box and drop the matches.

Another object of the invention is to provide means whereby the sliding drawer of such a box will remain in any position in which it is placed relative to the box cover.

Another object of the invention is to provide improved protection for match boxes of the above mentioned type, whereby sharp objects, coins, and the like, carried in the pocket will not be allowed to contact with the match heads. Ordinarily it is dangerous to carry a common paper box of matches in a pocket with metallic objects.

Still another object of the invention is to provide a simple and inexpensive device, for carrying out the above named objects, which may be quickly applied to one box and subsequently removed and applied to a second box when the first box is discarded.

Another important object of the invention is to provide simple means for reinforcing the ends of the sliding member of a match box or the like so that said member may be pressed upon, in the act of opening the box, without being collapsed and without accidentally dislodging the contents of the box.

The disadvantages of the common paper box and the wooden veneer box for carrying matches, particularly in the pocket, are well understood by all who are so accustomed to carry matches, and such advantages will be particularly set forth hereinafter, as the advantages of my invention are manifest.

I have illustrated by the accompanying drawings one practical embodiment, said drawings showing a complete match box

made in conformance with my invention, as well as a simple device, for attachment to a standard size of box for carrying out my invention.

In the said drawings,

Figure 1, is a perspective view of an ordinary type of match box which has been improved upon by the application of my invention. Figure 2 is a mid cross section of the embodiment shown in Fig. 1. Figure 3, is a longitudinal mid section of the said embodiment. Figure 4, is a perspective of the element which is added to the common box in order to provide the complete embodiment shown in Fig. 1. Figure 5, is a perspective of a modified embodiment of my invention. Figure 6, is a mid cross section thereof. Figure 7 is a plan view of a modification of the element shown in Fig. 4. Figure 8, is a view in longitudinal section of a box to which the element shown in Fig. 7 is applied. Figure 9 is a longitudinal section of a match box constructed solely of paper and in conformance with my invention.

A common paper match box cover is indicated in the drawings by the numeral 8, and is of the usual open end rectangular box construction. The sliding match containing member, which completes the usual match box of this type, is indicated in the drawings by the numeral 9. The cover comprises the walls 10, 11, 12 and 13, while the match containing member comprises a bottom wall 14, end walls 15 and 16, respectively, and side walls 17 and 18 respectively.

In constructing such a complete box, the sliding member is made a comparatively loose sliding fit, in fact because of the use of inexpensive material, it is not possible to have the sliding member fit snugly. If a snug or frictional fit is resorted to, then an end wall 15 or 16 may be crushed or torn in the act of pushing the sliding member into or out of its cover. When the end wall is so distorted, matches 20 may be displaced from the box between the top wall of the cover and the upper edge of an end wall, and so jam the sliding member.

Therefore it is advisable and customary in making a common match box of paper or wood veneer to make it a loose running fit. As is well known, the match container easily slips out of its cover and the matches are let loose in the user's pocket. Also, in opening the box and selecting a match, it is not un-

common for the container and all contained matches to fall out of the cover and be lost or wasted, while the useless cover remains in the hand.

5 To strengthen the end walls 15 and 16, and to reenforce the bottom wall 14 of the match container, and for the purpose of reenforcing the entire box from being crushed, as well as to provide friction for the sliding member, I provide contiguous metal reenforcing walls 22, 23 and 24, respectively, for walls 15, 14 and 16 respectively, of the sliding member.

Said contiguous reenforcing walls may be 15 provided in any suitable manner, and the walls may be of any suitably rigid material. Preferably the three reenforcing walls are provided in the form of a simple, single metal unit, such as is shown complete in 20 Figure 4. Said unit is merely a rectangular blank of metal having ends bent, as at 25 and 26 respectively, at substantially right angle to the intermediate portion or wall 23. In forming the unit, metal of slight spring 25 qualities is preferably employed, and the edges should be rounded as at 27 to eliminate sharp or objectionable corners. In bending up the edges, the distance between opposed bent vertical ends should be ordinarily slightly less than the normal length 30 of a sliding box member over which it is to fit. Thereby, when the metal unit is placed in position on the sliding member, as shown in Fig. 1, it will hold securely by friction 35 alone. Of course, when the sliding member is slid into the cover as shown in the drawings, then the unit is permanently held against dislodgment.

Now it will be apparent that the metal 40 bottom wall will increase the effective thickness of the sliding member and will make it a frictional or snug running fit in the cover. However, since the metal is smooth on the under surface, the sliding member 45 may be moved without undue force, but once having been moved to partial open position, or to any such position, its friction with the cover will hold it in that position against accidental dislodgment.

50 Instead of defeating the purpose of improvements by making it necessary to apply slight pressure in moving the sliding member, I have not only provided for holding the sliding member frictionally at any degree of opening, but I have provided reenforcement for the end walls so that even abnormal force may be applied without crushing the ends.

With the metal unit applied to an ordinary 60 paper or veneer match box, the box is reenforced against crushing either entirely or at the ends, the sliding member will hold in any adjusted position while a match is being removed, and the easily ignited heads of the 65 matches are fully protected from direct or

indirect contact with hard or sharp objects. When the paper box is depleted the metal unit may be applied to a new sliding member. Obviously, either the cover or the sliding member may be retained as long as it is 70 serviceable, or the cover itself may be more substantial and ornamental material, while common paper sliding members may be employed in conjunction therewith and replaced with each new supply of matches. 75

The bottom wall of the metal shown in Fig. 4 may be provided with an impediment in the form of a transverse ridge 30, which adds to the effective thickness of the drawer at central points, and which serves several purposes. Referring to Fig. 3, it will be seen that the impediment or ridge is truly central and tends to depress the bottom wall of the cover. The desired friction or brake action is thereby easily attained, and obviously the drawer may be moved to open position in either direction a distance equal to substantially one half the length of the box. As the drawer is moved outwardly there is an obvious tendency for the drawer to tilt slightly, with the result that one extreme end of the drawer will always be held in frictional engagement with the under surface of the top wall of the cover. In the form of the invention just described, the desired friction or brake action is obtained by virtue of a slightly natural resiliency possessed by the paper box structure, and particularly by the cover of the box.

The bottom wall of the metal unit may be bent very slightly along the line of the ridge so that it will tend to yieldably take up all clearance between a drawer and cover. In Fig. 3, the bottom wall of the metal unit is shown as being held in straight position by the natural strength of the paper box cover.

In the form of the invention shown in Figs. 5 and 6, there is provided a single rectangular ring of metal 32, which encompasses the side walls of the drawer. Thus the effective width of the drawer is increased, and when the so reenforced drawer is placed in the cover (see Fig. 7), it is a tight running fit. In this form of the invention the desired friction or brake action is obtained by virtue of the fact that the cover is distorted sidewise, and as a result the drawer is held frictionally between the top and bottom walls, respectively, of said cover. The metal ring acts as a reenforcement for the end walls of the drawer, as well as protecting the box as a whole against being crushed.

In the embodiment shown in Figs. 7 and 8, tongues, 35 and 36, respectively are struck out of the metal blank while being left attached, as at 37. Said tongues are each curved downwardly and outwardly, as at 38, in a gentle arc. Said tongues act as springs and are so formed that they each assume the position of that of the right hand tongue in 130

Fig. 8. In said figure the bottom wall of the cover is shown broken away at the point indicated by the numeral 39; therefore the tongue on that side is free to assume natural shape. The said modified embodiment functions substantially the same as the embodiment shown in Figs. 1 to 4, with the exception of the fact that the resiliency of the spring tongues is very largely depended upon to provide the necessary friction. This form will work well particularly in wood veneer boxes which are less pliable than paper boxes.

In Fig. 9 the invention is shown applied to and incorporated in a box which is supposed to be made solely of paper. In said form of the invention the top and bottom walls of the cover are each made with an indentation 45 and 46, respectively, while the drawer is made with a single and similar indentation 47. The indentation in the drawer is arranged to register with the indentation in the cover when the drawer is in closed position. When moved away from such position the indentation of the drawer rides out upon the surface of the bottom wall of the drawer and so tensions it as to provide the desired braking action.

It will be apparent from the foregoing that there are numerous ways in which my invention may be carried out, and I do not limit myself to any specific construction or arrangement of parts, and may alter the construction and arrangement of parts and incorporate the features of my invention in a match box in any way, as I desire, or as occasion requires, without enlarging the scope of my invention within the appended claims.

I claim:

1. In a match box reenforcing device, a rectangular sheet of metal having a rectangular horizontal portion and vertically ranging ends bent upwardly from the horizontal portion at substantially right angles; said horizontal portion being provided with a transverse bend about midway of its length; said bend yieldably inclining the bent ends slightly toward each other and providing a transverse depression of metal extending below the normal plane of the horizontal portion.
2. In combination with a match box having an open end cover and a drawer slidable therein; said drawer having a rectangular bottom wall and rectangular end walls, a sheet of metal contiguously coextensive of both end walls in both length and width, and further being contiguously coextensive of the bottom wall in both length and width; said sheet of metal being removable from said cover and adapted to slide therewith in said drawer, those portions of the metal sheet which are contiguously coextensive of the end walls of the cover being adapted for movement with said cover into said drawer, and either being capable of occupying substantially the entire cross sectional area of said drawer when the corresponding end of said drawer is intermediate ends of the cover.
3. In combination with a match box having an open end cover and a drawer slidable therein; said drawer having a rectangular bottom wall and rectangular end walls, a sheet of metal contiguously coextensive of both end walls in both length and width, and further being contiguously coextensive of the bottom wall in both length and width; said sheet of metal being removable from said cover and adapted to slide therewith in said drawer, and being held frictionally to the drawer by virtue of a tendency, of the portions which are contiguous with the end wall, to incline toward each other, those portions of the metal sheet which are contiguously coextensive of the end walls of the cover being adapted for movement with said cover into said drawer, and either being capable of occupying substantially the entire cross sectional area of said drawer when the corresponding end of said drawer is intermediate ends of the cover.

THOMAS M. BRINTNALL.
